UNITED STATES PATENT OFFICE.

BESSIE MENDELSON, OF MERRILL, WISCONSIN, ASSIGNOR OF ONE-HALF TO GILBERT MENDELSON, OF MERRILL, WISCONSIN.

REINFORCED SHOE-FLY.

1,145,784.

Specification of Letters Patent. Patented July 6, 1915.

Application filed January 31, 1914. Serial No. 815,733.

To all whom it may concern:

Be it known that I, BESSIE MENDELSON, a citizen of the United States, residing at Merrill, in the county of Lincoln and State of 5 Wisconsin, have invented new and useful Improvements in Reinforced Shoe-Flies, of which the following is a specification.

This invention relates to reinforcing devices, and particularly to reinforcing devices 10 for the button-holes of shoes or the like; and it has for its primary object the provision of a single length of flexible or pliable material that may be interposed between the folds of that flap of the shoe in which the button-holes are formed and which will extend the 15 entire length of the flap and arranged relatively of the outer ends of the button holes so as to positively prevent the same from tearing out or becoming unduly enlarged.

20 Another object of the invention is the provision of reinforcing means which will be applicable to the shoe upper of the ordinary well known form and which will possess such inherent qualities that will permit the 25 upper to be neatly and uniformly applied against the foot of the wearer.

With these and other objects in view, the invention consists of certain novel features of construction, combination and arrangement of parts, as will be hereinafter described and claimed.

30 In the accompanying drawings:—Figure 1 is a side view of a portion of a shoe flap, showing the application of the reinforcing means thereto; Fig. 2 is a section taken on line 2—2 of Fig. 1; Fig. 3 is a section on line 3—3 of Fig. 1; and Fig. 4 is a section on line 4—4 of Fig. 1.

The flap 1 of that portion of the shoe upper herein illustrated consists of two folds 40 or layers of material A and B which are stitched together in the usual manner, as at 2. The reinforcing member is preferably in the form of a single length of material such as copper wire or any other suitable flexible or pliable material that may be interposed 45 between the folds of material A and B so as to not interfere with the proper application of the flap against the foot of the wearer. The wire herein illustrated consists 50 of a main strengthening or reinforcing lead 3, which extends approximately for the full length of the flap 1 and the folds imme-

diate beyond the outer end of the button-holes 4. Above the upper hole the material 55 or wire is bent laterally, as at 5, so as to extend approximately for the full width of the flap, and it is then folded on itself to provide an upper lateral branch 6. At the opposite end, the main lead or branch 3 is 60 folded on itself to provide a relatively short auxiliary reinforcing member 7, which may be arranged between the rows of stitching 2 herein shown. The portion 6 may also be arranged between said rows of stitching 2 65 at the top of the flap and in this manner the device is securely held in position between the companion layers or folds of the flap without resorting to a foreign fastener, as will be appreciated. As thus arranged, the 70 device while strengthening the button holes serves additionally as a means to hold the flap of the uppers in a neat and uniform condition while it positively serves to reinforce all of the button-holes and to prevent the 75 same from tearing in the direction of the free marginal edge of the flap.

From the foregoing description, taken in connection with the accompanying drawings, the construction and operation of the 80 invention will be readily understood without requiring a more extended explanation.

Various changes in the form, proportion and the minor details of construction may be resorted to without departing from the 85 principle or sacrificing any of the advantages of this invention as claimed.

I claim:—

In a shoe, a fly comprising layers of material, and outer and inner hem stitches spaced 90 from one edge thereof, said fly having buttonholes spaced from the inner side of the inner hemstitches, and a reinforcing device comprising a single length of pliable wire arranged between said layers and between 95 said inner hem-stitches and the buttonholes, the ends of said reinforcing wire being doubled and arranged with their terminals between the inner and outer hem-stitches.

In testimony whereof I affix my signature 100 in presence of two witnesses.

BESSIE MENDELSON.
